UNITED STATES PATENT OFFICE.

SILAS M. FORD, OF ST. PAUL, MINNESOTA.

MACHINE FOR MAKING LATH-BOARD.

1,226,650.

Specification of Letters Patent. Patented May 22, 1917.

Application filed October 11, 1915. Serial No. 55,350.

To all whom it may concern:

Be it known that I, SILAS M. FORD, a citizen of the United States, residing at St. Paul, in the county of Ramsey and State of Minnesota, have invented new and useful Improvements in Machines for Making Lath-Board, of which the following is a specification.

This invention relates to a machine adapted to be used in making lath-board, and particularly that class of lath-board formed from paper or other suitable material impregnated with creosote compounds adapted to render the paper moisture proof and rot proof.

One object of my invention is to provide in the machine means whereby the paper or material to be made into lath-board may be fed into the machine from the original roll and automatically formed into a shape adapted to be used as a lath-board.

Another object of my invention is to provide a backing for the paper during the process of forming, so the paper may be held firmly and the form made of proper shape.

Another object of my invention is to provide means whereby a sharp bend may be made in the paper and sufficient tension put upon the paper to break the outside surface at the point of the bend.

Another object of my invention is to provide means whereby holes may be pierced in the paper in that portion of the lath-board that would correspond to the edge of a wooden lath, the primary object being to render it a simple and inexpensive operation to thread through the holes thus pierced, a flat wire or other suitable stiffening material.

Another object of my invention is to provide means in the machine for always assuring the proper alignment of parts, and particularly of those parts used directly in forming the shape of the lath-board.

Another object of my invention is to provide in the machine means for forming the paper into the form of lath-board of such nature that this means may be readily removed from the machine and replaced by a separate means that will form the paper into a different shape.

With these and incidental objects in view the invention consists in certain novel features of construction and combination of

parts, the essential elements of which are set forth in appended claims and a preferred form of embodiment of which is hereinafter described with reference to the drawings which accompany and form a part of this specification.

Figure 1 is a side elevation of a machine embodying my invention. Fig. 2 is a detail of a pair of chains carrying rectangular slats. Fig. 3 is a plan view of the machine shown in Fig. 1. Fig. 4 is an enlarged detail of the puncturing means carried in the slats, and Fig. 5 is a side elevation as viewed from the side opposite to that shown in Fig. 1.

The drawings disclose in Fig. 1 a side elevation of a machine embodying my invention in which 1, 2, 3 and 4 are shafts journaled in suitable bearings 5—5', 6—6', 7—7' and 8—8', respectively, supported by the frame of the machine 9, as better shown in Figs. 1 and 5, Fig. 5 being a reverse side elevation.

The shaft 3, Fig. 1, carries keyed thereto the driving pulley 10 by which the machine is driven from any suitable outside source of power.

The shaft 3 also carries keyed thereto a pair of sprocket wheels 11 and 12, Figs. 1 and 5, adapted to drive the chains 13 and 14, respectively, thus driving the sprocket wheels 15 and 16, which are keyed to the shaft 4.

The chains 13 and 14 have rigidly attached thereto at uniformly spaced intervals forming cleats 17, which may be of the shape shown in Fig. 1, or as shown in Fig. 2, as desired.

The spur gear 18, Fig. 5, also keyed to the shaft 3 drives through the spur gear 19 the shaft 1 to which the spur gear 19 is keyed.

A pair of sprocket wheels 20 and 21, similar to the sprocket wheels 11 and 12, are keyed to the shaft 1 and serve to drive the chain 22—22' similarly as the chains 13 and 14 are driven on the lower set of sprockets.

The chains 22 and 22' carry a set of forming cleats 23 similar to the forming cleats 17 on the lower chains, with the exception of the piercing pins 24, which are formed into a substantially rectangular piercing point at either end, better shown in Fig. 4, whereas the cleats 17 carry the openings 25, adapted to receive the ends of the piercing pins 24 during the operation of the machine.

Drums 26 and 26' are keyed to the shafts 1, 2, 3 and 4 and located between the pair of sprocket wheels on each shaft, as better shown in Fig. 3, which is a plan view of the 5 machine.

To operate the machine, the pulley 10 is revolved in a clock-wise direction by any suitable means, not shown, thus continuously carrying the chains 13 and 14 with 10 their forming cleats as an endless belt, traveling over the lower sets of sprocket wheels.

Driven by the spur gears 18 and 19, the shaft 1, drives the upper set of sprocket wheels, and thereby causes a continuous 15 travel of the chains 22 and 22' with their set of forming cleats 23, the cleats 17 and 23 alternately passing the line joining the axis of the shafts 1 and 3, with a certain amount of clearness between the two sets of 20 cleats at all times as they roll into and out of engagement.

In operating the machine, suitable paper or other material 27 is fed in while the machine is running, and this paper will be carried 25 by the cleats 23 down against the lower drum 26, the pressure between the two surfaces holding the paper firmly. The next cleat 17, traveling upwardly, will engage the paper and bend it at an acute angle 30 against the angular surface of the cleat 23 at that time associated with it.

The fold thus formed is carried forward, and the succeeding cleat 23 will press the paper over the edge of the cleat 17 just 35 preceding it, the paper at that time being pressed by the upper surface of the cleat 17 firmly against the upper drum 26.

It is evident that as the paper is pressed between the adjoining edges of the two 40 forming cleats, the piercing points of 24 will register with the holes 25 and pierce the paper at that point on both sides of the upper cleat, and the paper formed into a plaited form with the perforations made 45 and the piercing points remaining in the perforations, will be carried horizontally forward until the point X is reached, when the forming cleats will disengage themselves and leave the paper formed, as shown at Y 50 with the corner designated as A, so stretched or broken that the paper may, if so desired, be readily returned to the form which it had while traveling through the machine.

As the forming of the paper into the 55 plaited form is accomplished directly by the two sets of chains carrying the forming cleats, it is evident that by merely changing the chains, shown in Fig. 1, for chains similar to those shown in Fig. 2, the paper may 60 be formed into a rectangular corrugated shape, as illustrated in Fig. 2.

While I have described my invention and 65 illustrated it in one particular form I do not wish myself to be understood as confining myself to this particular construc-

tion, as it is evident my invention may be embodied in various ways and different constructions within the scope of the following claims.

Claims:

1. In a machine for making lath board, 70 of paper or other suitable material, the combination of rotatable means carrying thereon means for forming said material into a plaited form, and piercing means associated with said forming means adapted to pierce said material at regularly spaced intervals.

2. In a machine for making lath board 75 of paper or other suitable material, two drums, cleats associated with each of said drums and so positioned as to press material fed therebetween into a plaited form, the cleats associated with each drum holding said material firmly against the other drum while it is being formed, and piercing means associated with said cleats adapted 80 to pierce said material at regularly spaced intervals.

3. In a machine for making lath-board 85 of paper or other suitable material, the combination of rotatable means carrying thereon means for forming said material into a plaited form, means associated with said rotatable means for holding said material firmly against said forming means during 90 said operation and piercing means associated with said forming means adapted to pierce said material at regularly spaced distances.

4. In a machine for making lath-board 100 of paper or other suitable material, the combination of a sprocket wheel driving a sprocket chain, forming means carried by said sprocket chain adapted to form said material into the desired shape, and means 105 associated with said forming means for piercing said material at regularly spaced intervals.

5. In a machine for making lath-board 110 of paper or other suitable material, the combination of a pair of shafts, a sprocket wheel associated with each of said shafts, a sprocket chain coacting with said sprocket wheels, forming means carried by said sprocket chain adapted to force said 115 material into a plaited shape, a drum associated with said forming means and said sprocket chain, and means associated therewith for holding the material firmly against said drum while it is being formed into 120 said plaited shape.

6. In a machine for making lath-board 125 of paper or other suitable material, the combination of a sprocket wheel, a sprocket chain adapted to be driven by said sprocket wheel and carrying thereon forming means adapted to form said material into a plaited shape, means associated with said forming means for holding said material firmly against said forming means during 130 said

operation, and means associated with said forming means for piercing said material at regularly spaced intervals.

7. In a machine for making lath-board of paper or other suitable material, the combination of a shaft adapted to be driven by any suitable means, a pair of sprocket wheels on said shaft adapted to be rotated thereby, a second shaft with a pair of sprocket wheels attached thereto, a pair of chains connecting said sprocket wheels, so that said second shaft and sprocket wheels may be driven by said first shaft, a series of forming cleats carried by said sprocket chains, and means associated therewith for forming said material over said cleats as said machine is actuated.

8. In a machine for making lath-board of paper or other suitable material, the combination of a driving shaft adapted to be driven by any suitable means, having rigidly attached thereto a pair of sprocket wheels and a drum placed intermediate to said sprocket wheels, a second shaft carrying a pair of sprocket wheels, a pair of sprocket chains connecting similar sprocket wheels on said first shaft and said second shaft, forming cleats on said sprocket chains, means associated with said forming cleats for

forming said material over said cleats successively, and means associated with said cleats for piercing said material as said material is formed over said cleats.

9. In a machine for making lath-board of paper or other suitable material, the combination of two similar units, each of said units comprising a driving shaft, a pair of sprocket wheels rigidly attached to said shaft, a drum intermediate of said sprocket wheels and carried by said shaft, a second shaft adjacent thereto having a pair of sprocket wheels thereon, a second drum intermediate of said sprocket wheels on said second shaft and carried by said second shaft, a pair of sprocket chains connecting corresponding sprocket wheels on said shafts, forming cleats on said sprocket chains, each of said units forming said machine being mounted in a frame and so spaced one from the other, that the material fed to said machine will be formed into a plaited shape by said forming cleats, the forming cleats associated with one drum pressing the material tightly against the corresponding drum of the other unit during the act of formation.

SILAS M. FORD.
